STENCIL TYPING MACHINE

John L. Petz, Poughkeepsie, N. Y., assignor to
 International Business Machines Corporation,
 New York, N. Y., a corporation of New York

Application March 5, 1949, Serial No. 79,782

5 Claims. (Cl. 197—135)

1

This invention relates to typewriting machines. The broad object of the present invention is to provide an improved machine for typing addressing machine stencils.

An object is to provide a simple and efficient means of line spacing the stencils.

An object is to provide a simple and reliable means for automatically changing the ribbons from writing to stencilling position.

An object is to provide a simple means of automatically changing the line spacing of the stencil to enable identifying material to be written on the frame of the stencil and the platen spaced to the position for writing the first stencilled line.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the rear portion of a typewriting machine embodying the present invention and primarily shows the carriage of the machine.

Fig. 2 is a front elevation partly in section of the carriage.

Fig. 3 is a right side view of the carriage.

Fig. 4 is a left side view of the carriage.

Fig. 5 is a large scale view of the means for feeding the backing sheet and controlling the feed thereof.

Fig. 6 is a detail view showing the means for controlling the extent of feed of the backing sheet.

Fig. 7 is a vertical section showing the driving connections for the platen line spacing mechanism and the means for feeding the backing sheet.

Fig. 8 is a view of the stencil.

Fig. 9 is a detail view of the means for maintaining the ribbon in writing position during the typing of the identifying line on the frame of the stencil.

Fig. 10 is a detail view of the ribbon vibrator operating mechanism.

Fig. 11 is a detail view showing the platen line spacing mechanism.

Fig. 12 is a vertical section on the line 12—12 in Fig. 1 and shows the stencil in engagement with one of the driving treads therefor on the platen.

Fig. 13 shows the stencil in released position.

The invention is disclosed in the drawings as applied to the well-known "IBM" electric type-

2

writer, formerly known as the "Electromatic," solely for the purpose of illustration and it will be understood that the invention may be applied to other typewriting machines whether manually or power operated. Since the typewriter is well known in the art, only such of its parts as may be necessary to an understanding of the present invention will be described in detail.

The base of the machine is designated 10 in Figs. 1, 3, and 4 and carries the front rail 11 and the rear rail 12 (Figs. 3 and 4) which support the carriage 13 by means of suitable anti-friction rollers 14 in the well-known way. The carriage 13 comprises the side plates 15 and 16 (Figs. 1 to 4) which are integrally joined by a channel shaped member 17 to the underside of which is secured the usual escapement rack 18 cooperating with conventional escapement mechanism for effecting a step-by-step character spacing 20 movement from right to left (Fig. 1) when the usual character keys (not shown) of the machine are operated. The carriage is also provided with the usual tabulating rack 18 and marginal stop rack 19 secured to the plates 15 and 16 in a well known way. The marginal stop rack carries the usual marginal stops 20 which, in the present case, restrict the movement of the carriage to a very narrow zone to correspond with the width of the window in the stencil.

The plates 15, 16 are joined together at their upper rear corners by a cross rod 21 (Figs. 1 to 4) and this cross rod supports two plates 22 on which is removably mounted a rod 23 for supporting a roll of backing paper. In Fig. 1, the right-hand 35 end of the rod 23 is shouldered to fit in a hole in the right-hand plate 22 and the left-hand plate 22 has an open slot receiving a reduced portion formed in the left-hand end of the rod 23. The left-hand end of rod 23 is received in a round 40 hole in a spring retainer 24 (Figs 1 and 4) fastened to the left-hand plate 22 which retainer may be sprung to the left (Fig. 1) to permit the removal of a rod 23. The plates 22 are provided with inwardly projecting pins 25 (Fig. 1) which support the web of a backing sheet leading from a roll carried by rod 23. This backing sheet is not shown in order not to obscure the parts which lie underneath when the backing sheet is in place.

The plates 15 and 16 at their lower front corners (Figs. 3 and 4) support a cross shaft 26 on which are mounted the platen supporting arms 27 (Figs. 1 to 4, 12, and 13) which are located at the ends of the shaft 26 adjacent the plates 15 and 16. The arms 27 have open slots formed in their ends which rotatably support the platen

28, the platen being retained on the arms by the spring operated latches 29 which permit the removal of the platen 28 as a unit.

The platen 28 is provided with the usual line spacing ratchet 30 (Figs. 1, 2, 4, and 11) which is releasably coupled to the main part of the platen by means of a well known type of variable spacing clutch controlled by the button 31 in a well known way and the ends of the platen are provided with the usual platen rotating knobs 32. The central portion of the platen 28 which serves as a backing for the stencil material when typing a stencil, consists of a short rubber sleeve and, adjacent the ends of this sleeve, the platen is provided with the knurled driving wheels 33 which rotate with the rubber sleeve portion. The whole platen assembly may be rotated as a unit by means of either of the knobs 32 and, when the button 31 is pressed to the right (Fig. 1), the sleeve and the rubber wheels 33 are rotatable independently of the ratchet 30.

Pivoted mounted on the shaft 26 is a pair of arms 34 (Figs. 1, 2, 12, and 13) which also act as side guides in cooperation with the shorter sides of the stencil when inserting the stencil and the upper ends of the arms 34 are provided with small rollers 34a which bend the rear face of the stencil frame against the knurled rollers 33 for the purpose of line spacing the stencil. The arms 34 are spring urged in a counterclockwise direction (Figs. 12 and 13) by springs (not shown) and clockwise movement of the arms is limited by engagement of parts thereof with a fixed part of the machine to permit the platen to be retracted slightly without the rollers 34a following them all of the way for the purpose of inserting the stencil. Adjustably secured to the sides of the arms 34 are the stops 35 which limit downward movement of the stencil (designated S in Figs. 12 and 13). The stencil S is shown in Fig. 8 and comprises an open frame of stiff cardboard in which is mounted a strip ("window") of stencil paper.

It is desired first to write identifying matter, such as the addressee's name, on the top cross bar of the stencil frame, then to line space the platen 28 to bring the stencil portion into position for the writing of the first line and to effect the spacing of the subsequent lines of the address at shorter line space intervals than the initial spacing. In the present case, the first line of the stencil proper will be assumed to be triple spaced after the desired matter has been written on the top part of the stencil frame and subsequent lines of the address will be assumed as single spaced.

The stencil backing sheet passes over the pins 25 and between a feed roller 36 (Fig. 1) and a pressure roller 37. Thence the backing sheet extends over and between the fixed backing sheet guides 37 suitably supported in the framework and having side guide portions 37a extending at right angles to the platen 28 to guide the edges of the backing sheet. The backing sheet then passes around the front half of the rubber sleeve on the platen 28, underneath a single pressure roller 38, and may be torn off from time to time as the stencil operations proceed.

Means are provided for feeding the backing sheet at a considerably slower rate than the stencils and for this purpose the roller 36 is mounted on a shaft 39 (Fig. 5) which is journaled in the brackets 40, 41 secured to the channel-shaped member 17. At its left-hand end (Figs. 1 and 7) the shaft 39 is provided with a ratchet wheel 42

(see Figs. 5 and 6 also). Rotatably mounted on the shaft 39 adjacent the ratchet wheel 42 is a lever 43 (Fig. 5) on which is pivotally mounted at 39a the feed pawl 44 spring urged in a clockwise direction by the spring 45.

Normally, the nose of the pawl 44 engages a flange 46a (Fig. 6) formed in the spacing control lever 47 which is loosely mounted on the shaft 39. The flange 46a is formed in a spring finger 46 (Fig. 7) which is riveted to a curved lug formed in the lever 47 and this finger 46 has a narrowed portion yieldingly engaging teeth formed in an arcuate portion of the bracket 40 adjacent the ratchet 42 to hold the lever 47 in any of its set positions. A spring finger 42a carried by the marginal stop rack 19 (Figs. 1, 2, 5, and 7) prevents retrograde movement of ratchet 42.

The lever 43 is urged in a counterclockwise direction by a spring 48 (Figs. 5 and 7) and the arm opposite the pawl 44 has a roller 43a received in the bifurcated end of a lever 49 pivoted on the stud 50 carried by the bracket 40. The lever 49 has a link connection 51 (Figs. 1, 2, 5, and 7) to a rock lever 52 pivoted at 53a to a bracket 53 carried by the channel shaped member 17. The lever 52 has three arms, one of which has the link connection 51 aforesaid, and another of which is formed as a hook 52a (Figs. 2, 4, 7 and 11) to which is connected the usual carriage return tape 54.

When the carriage return key is depressed and the carriage return mechanism is rendered effective, the initial tension on the tape 54 rocks the lever 52 counterclockwise (Fig. 7) raising the link 51 and through the lever 49 rocking the lever 43 clockwise (Fig. 5). This causes the pawl 44 to ride off the flange 46a, after an extent of movement determined by the setting of the flange 46a, into engagement with a tooth in the ratchet 42 which then will be rotated an extent depending on the setting of the lever 47. By rotating the lever 47 in either direction (Fig. 6) the extent to which the ratchet 42 will be rotated may be varied.

A third arm of the lever 52 (Figs. 7 and 11) has a slot into which projects the lug 55a formed in the usual platen line spacing slide 55. The latter is best shown in Fig. 11. The line spacing mechanism is similar to the one disclosed in Patent 1,957,322 and includes a line space control lever 56 (Figs. 1, 2, 4, 7, and 11) pivotally mounted on a fixed stud 57 carried by the left-hand plate 15. This lever has a stud 56a (Figs. 1 and 11) which can cooperate with either of two notches formed in the line space stop arm 58 pivoted on a stud 59 carried by the plate 15. The slide 55 pivotally carries the line spacing pawl 60 (Figs. 7 and 11) which is normally held disengaged from the ratchet 30 by engaging the end of the stop arm 58.

The slide 55 is urged upwardly by a spring 61 (Fig. 7) coiled around the pivot 53a for lever 52 and engaging a pin carried by said lever 52 and a part of the channel shaped member 17. This spring tends to rock the lever 52 clockwise and thereby raise the slide 55 and is considerably stronger than the spring which urges the pawl into engagement with the teeth of the ratchet 30 so that normally the slide 55 is held in the position determined by the setting of the pin 56a in one of the notches 58a, 58b. The engagement of the arm 58 with the pawl 60 tends to rock the pawl clockwise to engage a portion of the latter with the edge of the slide 55 as shown

in Fig. 11, in which position the pawl 60 is clear of the ratchet 30.

With the pin 56a in the position of Fig. 11 in notch 58a, the arm 58 is held in its upper position allowing the maximum travel of the slide 55 downwardly and thereby the greatest line spacing. The notch 58a in the present case determines the triple spacing of the platen. When the lever 56 is thrown clockwise to carry the pin 56a into the notch 58b, the arm 58 and slide 55 will be cammed downwardly and reduce the amount that the slide 55 can restore to an extent to permit only one line space when the slide 55 is again drawn downwardly by the tape 54. As will be seen, means are provided to operate the lever 56 in this fashion, when line spacing after writing the first line on the frame, so that the platen will be triple spaced and at the same time the line spacing mechanism will be automatically set for single spacing for subsequent operations.

The pressure roller 37 is rotatable on a cross shaft 61 (Figs. 1 and 5) carried by the arms 62 which are journaled on the stud 50 carried by the bracket 40 and a similar stud carried by the bracket 41. Springs 63, of which there is one for each arm 62, urge the arm 62 in a counterclockwise direction (Fig. 5) to engage the pressure roller 37 with the feed roller 36. In a similar fashion, the roller 38 is mounted on a shaft 64 (Figs. 1 to 5 and 7) carried by the arms 65 also journaled on the studs 50. The arms 65 are urged in a clockwise direction (Fig. 5) by means of the toggle springs 66.

For the purpose of inserting the stencils, there is provided means for moving the platen backwardly away from typing position. Secured to the ends of the shaft 26 are the arms 67 (Figs. 1 to 4) to which are pivoted links 68. These links extend upwardly and toward the rear (Figs. 3 and 4) and are pivoted to levers 69 which, in turn, are pivoted at 15a and 16a to the plates 15 and 16, respectively. The links 68 are curved to pass around the pivots 15a, 16a and the pivots are in line so that the links 68 act substantially as toggle links. The levers 69 are provided with three arms, of which one of each is connected to a cross rod 70 (Figs. 1 and 2) so that the two levers 69 rotate as a unit on the pivots 15a, 16a. A second arm of each has connected thereto a spring 72 (Figs. 1 to 4) which is also connected to the pivot point of the corresponding link 68 to the arm 67 and tends to rock the levers 69 counterclockwise in Fig. 3 and clockwise in Fig. 4, but rotation of the levers is limited by contact of the links with the sides of the pivots 15a, 16a. It is apparent that when the levers 69 are rotated clockwise in Fig. 3, the links 68 will move away from the pivots 15a, 16a and be thrust downwardly rocking the shaft 26 counterclockwise from the position of Fig. 12 to the position of Fig. 13 and releasing the knurled wheels 33 from the rear face of the frame of the stencil or, if the stencil S is not in place, opening up a free space permitting the stencil to be inserted and pushed downwardly until arrested by the stops 35.

For the purpose of operating the levers 69 in this manner, there is provided the lever 74 (Figs. 1 to 4) which is journaled on the tie rod 21. The lever 74 has a wrist piece 74a, preferably formed of molded plastic, and is adjustably connected to an arm 75 also pivotally mounted on the rod 21. The arm 75 and the lever 74 are adjustably connected by the clamping bolt 76

(Fig. 3) which passes through a curved slot formed in the lug 74b comprising the extension of the lever 74 and is received in a round hole in a similar lug formed in the arm 75 so that the arm 75 may be adjusted relative to the lever 74. The arm 75 extends over a roller carried by the pivot pin 68a connecting the right-hand link 68 to the right-hand lever 69. When the arm 74 is pushed downwardly, as by resting the wrist on the wrist piece 74a, the arm 75 is thrust downwardly or counterclockwise (Fig. 3) thereby rocking the levers 69 clockwise and effecting the retraction of the platen.

With reference to Fig. 1, it will be seen that the operator may take a stencil, rest the wrist on the wrist piece 74a, and insert the stencil in front of the platen by practically one continuous movement thus reducing the number of operations necessary to insert the stencil to the absolute minimum. When the operator performs this operation, a stud 69a (Figs. 1, 2, 4, and 11) on the left-hand lever 69 moves to the rear of the machine and by engaging the arm 56, rocks the arm counterclockwise (Fig. 11) to move the lever 56 and pin 56a into the triple spacing position. Due to the shape of the arm between the notches 58a, 58b, and the position of the stud 57 in relation to this part of the arm, it is only necessary that the pin 56a be pushed out of the notch 58b so that by the pressure exerted by the spring 61 on the slide 55 which is communicated upwardly (Fig. 11) to the arm 58 by the pawl 60, the lever 56 will be snapped in a counterclockwise direction until it is stopped by the notch 58a which in reality is merely a stop shoulder on the arm 58 although it has a somewhat notched appearance.

The operator now proceeds to type on the upper part of the stencil frame and after completing this operation, presses the carriage return key to effect a return of the carriage and line space the platen three line spaces. A pin 60a on pawl 60 (Figs. 7 and 11) overlies an extension of the arm 56 and rocks the arm 56 in a clockwise direction (Fig. 11) when slide 55 moves downwardly, forcing the stop bar 58 to follow the slide 55 until the pin 60a again enters the notch 58b. When the tension on the carriage return tape 54 is slackened, the spring 61 will restore the slide 55 upwardly in Fig. 11 and it will be stopped after only the equivalent of a single line space movement of the slide due to the fact that the pin 56a is now in slot 58b. The platen will now be line spaced one line space at a time for each succeeding operation of the carriage return key until the lever 74 is again depressed.

The first line on the frame of the stencil is printed by means of the usual inking ribbon and, when the platen is line spaced to effect the initial triple-spacing operation, the ribbon vibrator mechanism is automatically shifted to stencil position. The ribbon vibrator mechanism may be the same as the one disclosed in Patent 1,950,762, but it will be understood, however, that other ribbon mechanisms may be used if desired and the disclosure herein of a particular form of ribbon vibrator mechanism is purely illustrative.

Fig. 10 illustrates the ribbon vibrator mechanism which includes a lever 77 pivoted at 78 to a fixed part of the machine. This lever has a link connection 79 to the universal bar usually provided in the machine for operating the ribbon mechanism so that the lever 77 is rocked clockwise a fixed amount each time a type bar is operated. The lever 77 has a T-shaped slot 77a

formed therein and received in the slot is a stud 81a carried by a link 81 pivoted at 82a to an arm 83 on the shaft 84. The stud 81a is connected to a link 85, the upper end of which is pivotally connected to an arm 86 pivotally mounted at 86a on a suitable stud. The free end of the arm 86 is pivotally connected to the ribbon vibrator 87, the upper end being provided with means for supporting the ribbon at the writing point.

Considering the shaft 84 as held in the position of Fig. 10, it is apparent that each oscillation of the lever 77 will raise the link 85 and the left-hand end of the arm 86, thereby elevating the ribbon vibrator 87 and the ribbon carried thereby to the printing position. The parts repeatedly move to this position during the writing of the first line and are automatically shifted by means of mechanism most clearly shown in Figs. 1, 3, 7, 9, and 10. The shaft 84, near the middle of the machine, has fixed to it an arm 88 (Figs. 3, 9, and 10) on the side of which is mounted a long pin 88a which extends from approximately the center of the machine to a point close to the right-hand side of the base 10 or approximately half the length of the carriage rails 11, 12. Pivotally mounted on the right-hand side of the bracket 41 (Fig. 9) is a latch lever 89 which is urged in a clockwise direction by a spring 90. A spring 91 urges the arm 88 in a counter-clockwise direction against the depending arm of the latch lever 89. Slidably mounted in the bracket 40 is a latch rod 92 which in Fig. 9 projects beyond the bracket 41 into the plane of the latch lever 89 and prevents rotation thereof under the combined tension of the springs 90, 91. With the parts in the position shown in Fig. 9, the shaft 84 will be held in the position of Fig. 10 thereby causing the ribbon to be raised to the writing position. The latch rod 92 extends well beyond the bracket 40 (Figs. 1 and 7) to a point more than half way to the plate 15 and has secured to it a small plate 92a lying in the path of rotation of a lug 52b in the lever 52.

When the stencil is triple spaced after writing the first line on the frame, the lug 52b travels to the left (Fig. 7) and pulls the rod 92 to the left sufficiently to move the right-hand end of the rod shown in Fig. 9 out of engagement with the lever 89, thereby permitting the springs 90, 91 to actuate the latch lever 89 clockwise and permit the spring 91 to actuate arm 88 and shaft 84 clockwise to cause counterclockwise movement of the shaft 84 (Fig. 10). This movement carries the pin 81a into the vertical part of the slot 77a so that the next operation of the lever 77 in typing the first line of the name and address will be idle and the ribbon will not be raised to the writing position. Thus, the name and address will be written in the window of the stencil without the use of the inking ribbon.

Cooperating with the pin 88a to which the spring 90 is anchored is a stud 26a (Fig. 9) carried by the shaft 26, the stud 26a being secured to a suitable collar carried by the shaft 26 to enable the position of the stud to be adjusted. When a new stencil is inserted, the shaft 26 is rocked counterclockwise to the position of Fig. 13, or clockwise in Fig. 9, thereby rocking the latch lever 89 positively in a counterclockwise direction. This allows a spring 93 (Fig. 1) curled around the latch rod 92 and interposed between the bracket 40 and a suitable collar on the rod 92, to push the rod 92 to the right with reference to Fig. 1 to again bring the right-hand end of the rod 92 into the position of Fig. 9 thereby

5 relatching the latch lever 89. This movement of the lever 89 actuates the shaft 84 clockwise (Fig. 10) to replace the stud 81a in the horizontal portion of the slot 77a (Fig. 10) in readiness for writing the matter on the frame of the stencil.

10 While there have been shown and described and pointed out the fundamental novel features of the invention as applied to a preferred embodiment, it will be understood that various omissions and substitutions and changes in the form 15 and details of the device illustrated and in its operation may be made by those skilled in the art without departing from the spirit of the invention. It is the intention, therefore, to be limited only as indicated by the scope of the following claims.

What is claimed is:

1. In a machine for typing on addressing machine stencils having a frame and a window 20 of stencil material, a carriage, a platen rotatably mounted in the carriage and having a backing roller for said window and knurled driving treads cooperating with the frame of the stencil on opposite sides of said window, stencil supporting and guiding fingers for holding said frame in engagement with said treads, said fingers including stops coacting with said frame to hold the stencil in a position to type an initial line on the top part of said frame, means to effect 25 a separation between said fingers and said treads to permit insertion of a stencil, and a manual lever for operating the separating means.

2. In a machine for typing addressing machine stencils having a frame and a stencil window, 30 a carriage, a platen rotatably mounted in said carriage and having a backing roller for said window and toothed driving members engageable with the sides of said stencil frame, spring actuated guide fingers for said stencil and having rollers for pressing the stencil frame against said toothed members and shaped to engage the sides of said frame to guide the stencil vertically, stop means associated with said fingers for holding the stencil with the top part of 35 said frame in a position initially to receive a first typed line, mechanism to line space said stencil to a second position to receive the first line on the stencil window and including a control lever settable to a first position to cause the spacing movement between said initial typing position and said second typing position to be effected differently from subsequent line spacing movements and settable to a second position to 40 change the line spacing for subsequent lines, means for mounting said platen for movement to open a passage for free insertion of said stencil between said platen and said rollers, a member for effecting said movement of said platen, means controlled by said member for shifting said lever 45 to said first position, and means for operating said line spacing mechanism including means to shift said lever to said second position concurrently with a line spacing operation.

3. In a machine for typing on a stencil having 50 a frame and a stencil window, a carriage, a platen having a backing portion for said window and a pair of feed wheels engageable with the rear faces of the sides of the stencil frame for feeding said stencil in a line spacing direction, means for mounting said platen on said carriage for limited rearward movement to permit insertion of a stencil in front of said backing portion, means to feed a backing sheet around said backing portion, line spacing mechanism to impart line-spacing rotation to said platen including a

member settable in a first line space position and in a second line space position to determine two different extents of line spacing of said platen and said stencil, a pair of guide fingers for guiding a stencil tangent to the platen and having means to press said stencil against said feed wheels and stop means for arresting a stencil inserted between said platen and said fingers with the top part of the stencil frame in a first line typing position, a manual lever for actuating the platen mounting means to separate said feed wheels from said fingers and thereby open a passage for free insertion of a fresh stencil and at the same time setting said member in its first line space position, ribbon control mechanism including a control lever settable in an active ribbon position by said manual lever and in an inactive ribbon position, means for operating the line spacing mechanism and the backing sheet feeding means after each line of typing on the stencil, means actuated by the line spacing mechanism for setting said member in its second line space position and means rendered effective by the operating means for setting the control lever in inactive ribbon position upon the operation of the line spacing mechanism after the first line is typed on the frame of the stencil whereby all subsequent lines on the stencil window will be typed without the ribbon and with a different line spacing.

4. In a machine for typing on a stencil having a frame and a stencil window, a carriage, a platen having a backing portion for said window and a pair of feed wheels engageable with the rear faces of the sides of the stencil frame for feeding said stencil in a line spacing direction, means for mounting said platen on said carriage for limited rearward movement to permit insertion of a stencil in front of said backing portion, means to feed a backing sheet around said backing portion, line spacing mechanism to impart line-spacing rotation to said platen including a member settable in a first line space position and in a second line space position to determine two different extents of line spacing of said platen and said stencil, a pair of guide fingers for guiding a stencil tangent to the platen and having means to press said stencil against said feed wheels and stop means for arresting

a stencil inserted between said platen and said fingers with the top part of the stencil frame in a first line typing position, a manual lever for actuating the platen mounting means to separate said feed wheels from said fingers and thereby open a passage for free insertion of a fresh stencil and at the same time setting said member in its first line space position, ribbon control mechanism including a control lever settable in an active ribbon position by said manual lever and in an inactive ribbon position, a latch for holding said control lever in the active ribbon position, means for operating the line spacing mechanism and the backing sheet feeding means after each line of typing on the stencil, means actuated by the line spacing mechanism for setting said member in its second line space position and means actuated by the operating means for releasing the latch upon the operation of the line spacing mechanism after the first line is typed on the frame of the stencil whereby all subsequent lines on the stencil window will be typed without the ribbon and with a different line spacing.

5. In a machine for typing a stencil having a frame and a stencil window, a platen, means to guide said stencil tangent to said platen for a line spacing movement thereof by said platen, line spacing mechanism including an operating lever therefor, ribbon control mechanism including a control lever settable in a ribbon active position and movable to a ribbon inactive position, a latch releasable by said operating lever for holding said control lever in ribbon active position, and a manual lever for actuating said control lever to said ribbon active position when inserting a new stencil in the guide means.
